My design consists of a square game board having a cruciform pattern of circular depressions thereon with a cluster of five circular depressions within a circle between each arm of the cruciform in combination with a rectangular channel extending around the entire periphery of the board. Said channel is divided into a series of compartments by walls extending at 45° angles from the corners of the board to the corners of the playing area, and subdivided by smaller walls or ridges extending perpendicularly between the periphery of the playing area and board, all as shown.

I claim:

The ornamental design for a game playing board, as shown and described.
